US0D1074923S

(12) **United States Design Patent** (10) **Patent No.:** **US D1,074,923 S**
(45) **Date of Patent:** **** May 13, 2025**

(54) **REFRIGERATOR FILTER**

(71) Applicant: **Qingsheng Huang**, Miluo (CN)

(72) Inventor: **Qingsheng Huang**, Miluo (CN)

(**) Term: **15 Years**

(21) Appl. No.: **29/981,582**

(22) Filed: **Dec. 31, 2024**

(51) LOC (15) Cl. **23-01**

(52) U.S. Cl.

USPC **D23/209**

(58) **Field of Classification Search**

(57) **CLAIM**

The ornamental design for a refrigerator filter, as shown and described.

DESCRIPTION

FIG. 1 is a front, left and top perspective view of a refrigerator filter, showing my design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and

FIG. 8 is an enlarged bottom plan view thereof; and,

FIG. 9 is an enlarged view of portion 9 shown in FIG. 1. The broken lines in the drawings illustrate the portions of the refrigerator filter, which form no part of the claimed design.

1 Claim, 9 Drawing Sheets
